HAT WELL

Joseph Polite, Royal Oak, Mich.

Application September 16, 1952, Serial No. 309,786

7 Claims. (Cl. 223—84)

1

This invention relates to hat holders or hat wells and is in the nature of an improvement in the hat holder or hat well device shown in my Patent No. 2,465,477.

In its illustrated embodiment the hat well or hat holder of the present invention comprises a support, a pair of semi-ovaliform members pivotally mounted on said support, and upper and lower relatively movable complementary brim shaping structures engageable with the opposite surfaces of a hat brim, the lower brim shaping structure comprising two semi-annular members each of which is mounted respectively on one of said semi-ovaliform members for movement therewith, the upper brim shaping structure being pivoted to said support to swing toward and away from said lower brim shaping structure. An object of the present invention is to provide an improved and simplified means responsive to the swinging of the upper brim shaping structure away from the lower brim shaping structure to move said semi-ovaliform members and the respective semi-annular members away from each other.

Other features and objects of the present invention will appear in the following description and appended claims, reference being had to the accompanying drawings forming a part of this specification wherein like reference characters designate corresponding parts in the several views.

Fig. 1 is a side plan view of a hat well, according to a preferred form of the invention.

Fig. 2 is a sectional view taken substantially through lines 2—2 of Fig. 1, looking in the direction of the arrows.

Fig. 3 is a fragmentary sectional view taken substantially through lines 3—3 of Fig. 1, looking in the direction of the arrows.

Fig. 4 is a top plan view of the hat well.

Fig. 5 is an enlarged sectional elevation taken substantially through lines 5—5 of Fig. 4 looking in the direction of the arrows.

Before explaining in detail the present invention it is to be understood that the invention is not limited in its application to the details of construction and arrangements of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings in detail, the hat holder or hat well embodied in the present inven-

2

tion comprises a base structure 10, a crown receptacle consisting of two semi-ovaliform halves 11 and 12, lower brim shaping halves 13 and 14 fastened to the crown receptacle halves 11 and 12 respectively, and an upper brim shaping member 15. As best seen in Fig. 4, each crown receptacle half is provided with an inwardly horizontally extending tab 16 apertured to receive a pivot stud 17 whereby the crown receptacle halves are pivotally fastened to the base. Diametrically opposite the tabs 16 each crown receptacle half is provided with a second inwardly horizontally extending tab 18 having a slot 19 therein. Headed studs 20 projecting through slot 19 and fastened to the base 10 serve to hold the crown receptacle halves on the base while permitting limited lateral swinging movement of the halves 11 and 12 relative to each other about the pivot studs 17.

The lower brim shaping halves 13 and 14 when placed in juxtaposition and the upper brim shaping member 15 are of a configuration conforming to the general shape of a hat brim and are provided with opposed concave and convex interfitting faces.

The base 10, the material of which may be metal, plywood or plastic, has fastened thereto at each end upstanding post members or stanchions 21 and 22. The stanchions are illustrated as having channel shaped cross-sections but may be of any configuration having the desired structural rigidity. The stanchion 22 provides a support for the pivotal mounting of the upper brim shaping member 15. The upper brim shaping member 15 is fastened in any suitable manner, as by means of screws 15a to a longitudinally extending rib member 23 which also functions as a hand grip member. Additional cross ribs 24 may be provided to provide for further structural reinforcement of upper brim shaping member 15. The rib or hand grip member 23 is journalled at one end for swinging movement on a pin 25 secured to the upper end of the post member or stanchion 22. At its other end the rib or hand grip member 23 has fastened thereto a spring clip member 26 adapted to selectively engage any one of a series of notches or projections 27 formed on the upper outer surface of the stanchion 21. As best viewed in Fig. 5, the rib or hand grip member 23 is provided with a slot 28 through which the pivot pin 25 passes. A thumb screw 29 is threaded through a tapped hole in the hand grip member or rib 23 into engagement with the pin 25. The thumb screw 29 at the one end of the member 23 in conjunc-

tion with the selective relationship of the spring clip 26 on the other end thereof with the notches or projections 27 thereon provides a construction and arrangement whereby the upper brim shaping member 15 is adjustable relative to the lower brim forming halves 13 and 14 to accommodate hats of different material thicknesses.

An important feature of the present invention is the provision of a simplified and efficient mechanism for automatically swinging the crown receptacle halves 11 and 12 including their attached lower brim forming halves 13 and 14, laterally away from each other upon upward swinging movement of the upper brim shaping member 15 thereby facilitating the insertion or withdrawal 10 of the hat H within or from the hat well. On its outer surface near the lower edge thereof each crown receptacle half 11 and 12 respectively has fastened thereto a vertically extending tab 30 and 31, the tabs normally being spaced a slight distance apart. A shaft 32 is suitably journaled in a bracket 33 fastened to the base 10 between the crown receptacle halves 11 and 12 and the post or stanchion 22. The shaft 32 has formed on its left end, as viewed in the drawings, a looped portion 34 adapted when in a vertical position to stand between the tabs 30 and 31. At its other end adjacent the stanchion 22 the shaft 32 has a laterally extending arm 35 forming in effect a bell crank. The arm 35 is operatively connected to the hand grip member 23 by a vertically extending rod 36 pivotally connected at its upper end to the hand grip rib or member 23 and having a looped section 37 at its lower end adapted to receive the arm 35.

In the operation or use of the invention, to insert a hat, the operator disengages the spring clip 26 from the holding notches or projections 27 and swings the hand grip rib or member 23 from its solid line position to its dotted vertical line position, as shown in Fig. 1. The upward swinging movement of the hand grip member 23, carrying therewith the upper brim shaping member 15, results in an upward movement of the vertical rod 36. This causes the shaft 32 to rotate through approximately 90° resulting in the looped portion 34 thereon assuming a horizontal position thereby spreading the tabs 30 and 31. The spreading of the tabs 30 and 31 causes the crown receptacle halves 11 and 12 to swing away from each other. A spring means is provided to restore the crown receptacle halves to their normal position when the upper brim shaping member 15 is permitted to swing down to its closed position. As illustrated, the spring means consists of a coil spring 38 attached at each end to an apertured ear or lug 39 formed in the side of the crown receptacle halves 11 and 12 respectively.

A pivoted blocking member 40 is provided which when the hand grip member 23 is in a vertical position may be positioned for engagement by a pin 41 extending from the end of the member 23. This construction is for the purpose of providing a means for holding the upper brim shaping member in open position while inserting or removing a hat.

The foregoing construction and arrangement as described forms an efficient and inexpensive hat holder or hat well capable of conveniently holding a hat and also preserving the shape of the brim.

I claim:

1. A hat well comprising a base, a pair of semi-ovaliform members having semi-annular rim portions, means pivotally mounting said mem-

bers on said base for pivotal lateral movement relatively to each other, an annular member, said annular member and said semi-annular rim portions forming upper and lower complementary brim shaping structures engageable with the opposite surfaces of a hat brim, means supporting said annular member for swinging movement from a closed position to an open position relative to said semi-annular rim portions, bell crank means mounted on said base and having a part thereof in abutting relation to a part of each semi-ovaliform member, and link means connecting said bell crank means to said annular members, said link means upon swinging of said annular member to an open position actuating said bell crank means to cause said part thereof to abut said parts of the semi-ovaliform members and thereby pivotally separate the same.

2. A hat well comprising a base, a pair of semi-ovaliform members having semi-annular rim portions, means pivotally mounting said members on said base for pivotal lateral movement relatively to each other, an annular member, said annular member and said semi-annular rim portions forming upper and lower complementary brim shaping structures engageable with the opposite surfaces of a hat brim, means supporting said annular member for swinging movement from a closed position to an open position relative to said semi-annular rim portions, bell crank means mounted on said base and having a part thereof in abutting relation to a part of each semi-ovaliform member, link means connecting said bell crank means to said annular member, 25 said link means upon swinging of said annular member to an open position actuating said bell crank means to cause said part thereof to abut said parts of the semi-ovaliform members and thereby pivotally separate the same, and spring 30 means adapted to restore said semi-ovaliform members to their normal position upon said annular member being swung to a closed position.

3. A hat well comprising a support, a pair of semi-ovaliform members pivotally mounted on said support and forming a recess adapted to receive the crown portion of a hat, upper and lower complementary brim shaping structures adapted to engage the opposite surfaces of a hat brim, the lower brim shaping structure comprising two semi-annular members each of which is mounted 45 respectively on one of said semi-ovaliform members for movement therewith, means pivotally mounting said upper brim shaping structure on said support for swinging movement toward and away from said lower brim shaping structure, spreader means journaled on said support and having a part thereof engageable with each of said semi-ovaliform members, and link means connecting said spreader means to said upper structure to transmit swinging movement of said upper structure away from said lower structure to said spreader means and cause the said part thereof to engage said semi-ovaliform members and move the same away from each other to enlarge said recess.

4. A hat well comprising a support, a pair of semi-ovaliform members pivotally mounted on said support and forming a recess adapted to receive the crown portion of a hat, upper and lower complementary brim shaping structures adapted to engage the opposite surfaces of a hat brim, the lower brim shaping structure comprising two semi-annular members each of which is mounted respectively on one of said semi-ovaliform members for movement therewith, means

pivotsly mounting said upper brim shaping structure on said support for swinging movement toward and away from said lower brim shaping structure, spreader means journaled on said support and having a part thereof engageable with each of said semi-ovaliform members, and link means connecting said spreader means to said upper structure to transmit swinging movement of said upper structure away from said lower structure to said spreader means and cause the said part thereof to engage said semi-ovaliform members and move the same away from each other to enlarge said recess, and spring means connected to said semi-ovaliform members and adapted to move the same in the opposite direction upon said upper structure being swung toward said lower structure.

5. A hat well comprising a support, said support comprising a base portion and a column portion, a pair of semi-ovaliform members independently pivotally mounted on said base portion and forming a recess adapted to receive the crown portion of a hat, upper and lower complementary brim shaping structures adapted to engage the opposite surfaces of a hat brim, the lower brim shaping structures comprising two semi-annular members each of which is mounted respectively on one of said semi-ovaliform members, means pivotally mounting said upper brim shaping structure on said support column portion for swinging movement toward and away from said lower brim shaping structure, and a spreader means mounted on said support having a part thereof connected to said upper structure and a second part thereof operatively engageable with said semi-ovaliform members to pivotally move the same to enlarge said recess upon said upper structure being swung away from said lower structure.

6. A hat well comprising a support, said support comprising a base portion and a column portion, a pair of semi-ovaliform members independently pivotally mounted on said base portion and forming a recess adapted to receive the crown portion of a hat, upper and lower complementary brim shaping structures adapted to engage the opposite surfaces of a hat brim, the lower brim shaping structures comprising two semi-annular members each of which is mounted respectively on one of said semi-ovaliform mem-

bers, means pivotally mounting said upper brim shaping structure on said support column portion for swinging movement toward and away from said lower brim shaping structure, and a spreader means mounted on said support having a part thereof connected to said upper structure and a second part thereof operatively engageable with said semi-ovaliform members to pivotally move the same to enlarge said recess upon said upper structure being swung away from said lower structure, and spring means connected to said semi-ovaliform members and adapted to move the same in the opposite direction upon said upper structure being swung toward said lower structure.

7. A hat well comprising a support, said support comprising a base portion and a column portion, a pair of semi-ovaliform members independently pivotally mounted on said base portion and forming a recess adapted to receive the crown portion of a hat, upper and lower complementary brim shaping structures adapted to engage the opposite surfaces of a hat brim, the lower brim shaping structures comprising two semi-annular members each of which is mounted respectively on one of said semi-ovaliform members, means pivotally mounting said upper brim shaping structure on said support column portion for swinging movement toward and away from said lower brim shaping structure, and bell crank means journaled on said base portion, said bell crank means having a lever arm at one end and a part at the other end engageable with a part of each semi-ovaliform member, link means connecting said lever arm and upper structure to transmit swinging movement of the latter to said bell crank means, said bell crank means part when moved in one direction upon movement of said upper structure away from said lower structure engaging said semi-ovaliform member parts and pivotally moving said semi-ovaliform members in a direction to enlarge said recess.
